UNITED STATES PATENT OFFICE.

LUTHER L. YATES, OF SAN FRANCISCO, CALIFORNIA.

REFRIGERATOR CAR.

Application filed July 31, 1920, Serial No 400,447. Renewed June 20, 1922. Serial No. 569,717.

To all whom it may concern:

Be it known that I, LUTHER L. YATES, a citizen of the United States, residing at San Francisco, in the county of San Francisco and State of California, have invented a new and useful Improvement in Refrigerator Cars, of which the following is a specification.

This invention relates to improvements in railway cars and more particularly to refrigerator cars.

Cars of this general type are usually provided with hatches adjacent to each end and it is the object of this invention to apply the insulation for the top of the car in one continuous sheet, from side to side and between the hatches.

The insulation extending continuously from end to end and continuously from side to side of the car as applied in accordance with the invention not only simplifies the construction of the car, but also adds to its efficiency as a refrigerator unit.

While the preferred form of this invention is illustrated upon the accompanying sheets of drawings, yet it is to be understood that minor detail changes may be made without departing from the scope thereof.

Figure 1 is a top plan view of a portion of a car of this type with the roof removed illustrating the insulation for the top of the car applied in accordance with this invention.

Figure 2 is a view in transverse section taken on the line 2—2 of Figure 1, illustrating the roof in place.

Figure 3 is a view in transverse section taken on the line 3—3 of Figure 1, illustrating the means for securing the insulation for the top of the car.

Figure 4 is a detail sectional view taken on the line 4—4 of Figure 3.

Cars of this type are usually constructed with an inner sheathing of wood about the sides and top with layers of insulation material between the sheathing and the sides and roof. In building the car, the sides and ends are first erected upon the car body, the insulation material placed about the side, the inner sheathing applied to the sides and top, the top insulation installed, then the carlines and roof placed thereover.

In accordance with this invention after the top sheathing 1 extending from end to end and between the side plates 2 is in place and secured to these parts in the usual man-

ner, a sub carline 3 is laid on the top sheathing under the position to be occupied by each main carline. An insulation supporting sheathing 5 is laid from end to end and from side to side upon the sub carlines and is supported thereby leaving an air space between the sub carlines, top sheathing 1 and supporting sheathing 5. The insulation material 6 in continuous sheets of slightly greater width than the distance between the side plates is laid upon the supporting sheathing from hatch to hatch and may be made up of as many layers or of such material as desired.

While the main carlines 4 are illustrated as being of a particular type any form of carline that is provided with a horizontal bottom portion may be employed. The main carlines are then placed in position and forced down upon the layer or layers of insulation material over each sub carline. The insulation material is compressible and the sub carlines are constructed and secured in such a manner that when the main carlines are in place to be secured to the side plates they will have compressed the insulation material sufficiently to positively hold it against the shocks to which the car is subjected in starting and stopping or against the weaving action of the car while in motion.

The insulation material is slightly wider than the width of the car and is secured by wooden cleats 7 nailed or otherwise secured through the edges of the sheet to the side plates between the carlines on the upper side of the sheet. These cleats compress the insulation between the supporting sheathing and side plates and hold the edges in position while the central portion is held between the sub and main carlines.

As there are usually two hatch openings at each end of the car whose sides 8 are extended downward through the top sheathing 1, it is necessary to apply sections of insulation about them or make apertures in the continuous sheets to accommodate the openings. The insulation material is secured about the sides of the hatches and to the end plates of the car by cleats in the same manner as it is secured to the side plates.

What I claim is:

1. In a refrigerator car, side and end plates, a sheathing extending across the top of the car between the end and side plates,

subcarlines between the side plates above the sheathing, a continuous sheet of insulation material supported upon the subcarlines, and main carlines each having a horizontal bottom portion engaging the insulation material above the subcarlines, and cleats between the main carlines securing the edges of the sheet to the side plates.

2. The method of applying insulation to the top of a refrigerator car comprising the erecting of the sides and ends of the car, the

construction of the top sheathing, the placing of subcarlines thereover, the applying of a continuous sheet of insulation material of greater width than the car and forcing said sheet between the side plates to rest upon the subcarlines, the forcing of main carlines above the subcarlines to compress the sheet between them, and the securing of the edges of the sheet to the side plates by cleats.

LUTHER L. YATES.
